ELECTRIC WIRE WRAPPING MACHINE

Filed March 3, 1925

2 Sheets-Sheet 2

UNITED STATES PATENT OFFICE.

ERNEST G. BROWN, OF NEW HAVEN, CONNECTICUT, ASSIGNOR TO THE ACME WIRE CO., OF NEW HAVEN, CONNECTICUT, A CORPORATION.

ELECTRIC-WIRE-WRAPPING MACHINE.

Application filed March 3, 1925. Serial No. 12,900.

My invention relates to electric wire wrapping machines of which the following, when taken in connection with the accompanying drawings and the characters of reference 5 marked thereon, is a full, clear, and exact description, and which said drawings constitute part of this application, and represent, in—

Fig. 1, a broken view in front elevation 10 of one form which a machine constructed in accordance with my invention may assume.

Fig. 2, a top or plan view of the polishing-unit with the frame broken away.

Fig. 3, a view in vertical section on the 15 line 3—3 of Fig. 2.

My invention relates to an improvement in machines for wrapping electric wire with insulating material, such as silk or cotton, the object being to greatly improve the 20 quality and appearance of the product without materially increasing its cost.

With these ends in view, my invention consists in a wire-wrapping machine characterized by the independent rotation about 25 the wire of the wrapping and the polishing units of the machine, whereby they may be run in opposite directions.

In carrying out my invention, as herein shown, the insulating material, in the form 30 of a narrow, unwoven ribbon of filaments 5 is fed through a guide 6 from a spool 7 carried by a cup-like spool-holder 8 mounted on a vertically-arranged spindle 9 having a central, longitudinal passage 10 through which the 35 wire 11 is drawn upward by any suitable means from a source of supply located below the machine. The said spindle has bearing in and is supported by the horizontal lower member 12 of a suitable frame, and mounts 40 a pulley 13 connected by a crossed belt 14 with a driving-pulley 15 on the lower end of a driving-shaft 16, also having bearing in the said frame-member 12. The parts thus far described constitute what I may 45 term the "wrapping-unit" of the machine.

Turning now to the polishing-unit of the machine, the upper end of the said driving-shaft 16 has bearing in a horizontal upper frame-member 17 and mounts a pulley 50 18 connected by a belt 19 with a pulley 20 on a vertically-arranged spindle 21 located above and in line with the spindle 9 aforesaid and running in two ball-bearings to which I have applied the general reference 55 character 22, and which are mounted in a bi-

furcated arm 23 offsetting from the upper frame-member 17. The said spindle 21 has a central axial passage 24 located in line with the corresponding passage 10 of the shaft 9, while its upper end is partially cut away transversely, as at 25, for the exposure of the wrapped wire to the action of the polishing-plate 26, which presses the wire against the smooth walls of a substantially semi-circular groove 27, which virtually 60 forms a part of the passage 24, and results from cutting the upper end of the spindle 21 away, as at 25, to expose the wrapped wire. As shown in Fig. 2, the spindle is 65 transversely cut away something more than 70 one-half for such exposure of the wrapped wire, but the character of the cut is immaterial, so long as a portion of the wrapped wire is exposed to the contact of the polishing-plate 26. The said plate 26 has a 75 shank 28 passing outwardly through a hole 29 in the horizontal arm 30 of a polisher-head 31, pivotally mounted upon the upper end of a vertical post 32, the lower end of 80 which is mounted in a collar 33 secured to the spindle 21 just below the transversely cut-away portion 25 thereof. The polishing-plate 26 is loosely held in the arm 30 by two pins 34 passing through the shank 28 on opposite sides of the arm 30. For 85 forcing the polishing-plate 26 into engagement with the wrapped wire, as it travels upward through the machine, I employ a helical spring 34 encircling the post 32 and having its upper end entered into the head 31, while its lower end is entered into the 90 post, as shown in Fig. 1.

Heretofore, in wire-covering machines of the character described, the polishing device, whatever its character, has been organized 95 with the wrapping-mechanism so as to rotate therewith around the wire as upon an axis.

In my improved mechanism, on the other hand, the means for applying the insulation and for polishing the same are independently organized, so that the speed of the polisher may be regulated so as to secure 100 the best results with any given size of wire, any type of fibre insulation, and any conditions of temperature and humidity.

While I do not limit myself to any specific mode of operation, I have secured the best results by rotating the polishing-unit in the opposite direction from the wrapping-unit. 110

In the operation of the machine, the wire 11 is drawn upwardly by any suitable means in the customary manner through the hollow spindles 9 and 21. As it emerges from the 5 upper end of the spindle 9, it is spirally wrapped with a ribbon of silk or cotton threads 5 rapidly revolved about it by the spindle. So wrapped, the wire travels upward through the spindle 21, ultimately 10 passing under the polishing-plate 26, which revolves about it with the spindle 21 and smooths it, so that all trace of the joints between the convolutions of the ribbon 5 are eliminated and so that it presents a highly polished, unbroken surface of minute fila-

ments, which will not be appreciably disrupted when the wire is bent and which provide adequate insulation for it.

I claim:

In a machine for wrapping electric wire, 20 the combination with separately-organized wrapping and polishing units, of means for revolving the same in opposite directions around the wire, as the same is successively subjected to the action of the said independently-organized wrapping and polishing units. 25

In testimony whereof, I have signed this specification

ERNEST G. BROWN.
